UNITED STATES PATENT OFFICE.

GIUSEPPE NIGRA, OF TURIN, ITALY, ASSIGNOR TO O. M. I. M. OFFICINA MECCANICA
INDUSTRIA MAGLIERIA, OF TURIN, ITALY, A COMPANY.

APPARATUS FOR THE MANUFACTURE OF FANCY KNITTED FABRICS ON CIRCULAR-KNITTING FRAMES.

Application filed April 6, 1926, Serial No. 100,136, and in Italy April 10, 1925.

This invention relates to the manufacture and will each time it is moved cause the reversal of threads f_1 and f_2 so alternately causing one to appear on the face and the other at the back of the fabric. 55

5 designs either by merely periodically reversing two threads of different colour to obtain vertical stripes, or to obtain varied patterns, such as rhombic, square or like figures means may also be provided for instantaneously reversing the threads.

10 The apparatus operates in the following manner:

Two threads of different colours exchange 15 positions (i. e. are reversed) at predetermined intervals with respect to the needle whereby the stitches of the respective colours are visible sometimes on the face and sometimes on the back of the fabric, thus forming a pattern of one colour upon the 20 foundation of another colour.

The apparatus comprises an arrangement 25 for reversing two threads of different colours upon the needle and another arrangement for varying according to the pattern desired the moment in which the reversing arrangement comes into action.

The invention is illustrated in the accompanying drawings, in which Figure 1 is an 30 end elevation of the operating disk and a plan view of the reversing levers, Figure 2 is a side view of the reversing levers and a plan view of a portion of the operating disk. Figure 3 is a side elevation partly in section of the controlling means mounted on a shaft 35 radial with respect to the frame.

The reversal arrangement comprises two hook levers 1 and 2 guiding the differently coloured threads f_1 and f_2 , and a third lever arm 3. The three levers are pivoted respectively at I, II and III, on a suitably shaped 40 stirrup 4, suitably fixed to the frame. The rear end of lever 1 is pivoted to the lever 2 at 5, and to the lever 2 at the pivotal point 5, the arm 6 of the lever 3 is pivoted. The 45 lever 3 acts on arm 6 of lever 3, which carries at the end of its arm a roller 7. The lever 3, when acted on, forces levers 1 and 2 reciprocally to exchange their positions; and for this purpose roller 7, under the action 50 of a spring (not illustrated) enters into or comes out of notches 8 suitably distributed over a rotating disk 9 or the like.

On the rotation of disk 9 roller 7 will successively engage and come out of notches 8

Referring to Figure 3, 9 is a disk similar to disk 9 in Figures 1 and 2, suitably mounted upon a shaft 10 upon which is keyed a toothed wheel 11 placed in rotation by the rotating plate of the frame, for example, through a rack 12 fixed thereto. The shaft 10 is supported, for example, by a stirrup 13 carried by a plate 14 fixed to the frame, in any convenient manner. As illustrated 15 is one of the needles, 16 one of the sinkers and 17 a means for anchoring the needles upon the rotating plate, although 20 this of course forms no part of this invention.

Disk 9 is by toothed wheel 11 rotated at a constant speed with the frame and it will easily be seen that roller 7 on engaging and 25 passing out of notches 8 on the disk will cause levers 1 and 2 to be given corresponding periodic reversal; the colour of the threads will also be reversed, having for effect to form alternating vertical stripes on 30 the fabric.

If other patterns are desired it will be necessary to effect the reversal of the thread at predetermined differing intervals and not at periodic constant intervals. According to 35 this invention this is obtained by giving to the disk 9 additional partial rotations whether in the same direction of rotation or in the contrary direction of rotation, i. e. giving an advance or a lag to the period at 40 which roller 7 will engage or come out of the notches on the disk.

For this purpose the disk 9 is mounted in the following manner:

Upon the shaft 10 there is provided a loose drum 18 having a flange to which disk 9 is secured. Drum 18 is fast with a worm wheel 19 in mesh with a worm 20. Worm 20 is carried by a disk 21 fast with the shaft 10 and itself receives rotary movement 100 through a pair of bevel wheels 22, 23, carried by disk 21. Upon the spindle of bevel wheel 23 is keyed a ratchet wheel 24 having large teeth in which can engage a spring 105 pressed rod 25 guided in a dashpot 26 and actuated by any control member at a suitable time, for example, by lever arm 27 whose other arm is moved in the direction of the

arrow by a flexible transmission controlled by any regulating apparatus or "counter" not illustrated.

When the regulating apparatus is inoperative and the rod 25 is out of engagement with the ratchet wheel 24, as shown in the drawing, the toothed wheel 11 rotates disk 21, and in view of the friction of the worm 20 and worm wheel 19, the drum 18 and the disk 9 are also driven. Disk 9 thus rotates at a constant speed whereby the levers 1 and 2 of Figure 1 will be periodically reversed in position and thus the colours of the threads.

15 When, however, rod 25 is brought into action and engages between two teeth on ratchet 24, then owing to the movement of rotation given to ratchet 24 by the disk 21 around the shaft 10, it is forced to make a 20 partial rotation upon its own axis; this rotation is transmitted through bevel wheels 23 and 22 to worm 20, worm wheel 19 to drum 18 and to disk 9, imparting to this an additional movement of rotation.

25 Notches 8 on disk 9 will thus come opposite the roller 7 at positions relatively different from that which took place in the procedure before described and each will produce its effect with a displacement of the 30 side at which the colour stripe appears with respect to the effect produced by the same groove during a previous rotation or series of rotations. The colour stripe, or the reversal of the two threads, is for this reason 35 suitably displaced, and by combining in different manners the relations of the pinions and of the couple, worm and worm wheel with the apparatus controlling the locking rod, most varied patterns may be obtained.

40 In the method of carrying out the invention illustrated, to impart a positive or negative additional rotation of the disk 9 rod 25 is caused either to engage between the teeth on the toothed wheel above (as indicated in the drawing) or below the axis of 45 rotation of the toothed wheel 24 so that it will effect a relative rotation to the right or to the left around its own axis.

It will be easily seen that the arrangement for giving an additional rotation to 50 disk 9, as well as the lock members varying the moment at which it is brought into operation, may be different from the forms illustrated without departing from the scope of the invention. 55

What I claim as my invention is:

1. In a circular hosiery knitting machine, the combination of a pair of thread guides situated in different planes, means operated by a notched disk for acting on said thread 60 guides, a rotated shaft on which the disk is loosely mounted, a worm wheel fast with the disk, a worm in mesh with the worm wheel, a disk fast with the shaft and carrying the worm, and means for periodically 65 rotating said worm on its own axis.

2. In a circular hosiery knitting machine, the combination of a pair of thread guides situated in different planes, means operated by a notched disk for acting on said thread 70 guides, a rotated shaft on which the disk is loosely mounted, a worm wheel fast with the disk, a worm in mesh with the worm wheel, a disk fast with the shaft and carrying the worm, a pair of toothed wheels 75 in mesh with each other, one of said wheels being fast with the worm, and means for causing said other toothed wheel periodically to be rotated about its own axis.

3. In a circular hosiery knitting machine, 80 the combination of a pair of thread guides situated in different planes, means operated by a notched disk for acting on said thread guides, a rotated shaft on which the disk is loosely mounted, a worm wheel fast with 85 the disk, a worm in mesh with the worm wheel, a disk fast with the shaft and carrying the worm, a pair of toothed wheels in mesh with each other, one of said wheels being fast with the worm, a ratchet fast with 90 the other said toothed wheel, a plunger, and means for moving said plunger into the path of the said toothed wheel.

In testimony whereof I have signed my name to this specification.

GIUSEPPE NIGRA.
